UNITED STATES PATENT OFFICE.

FRANK TAMBORELLO, OF MILWAUKEE, WISCONSIN.

REVERSIBLE COLLAR.

Application filed October 12, 1922. Serial No. 594,002.

To all whom it may concern:

Be it known that I, FRANK TAMBORELLO, a citizen of the United States, and resident of Milwaukee, in the county of Milwaukee and State of Wisconsin, have invented certain new and useful Improvements in Reversible Collars; and I do hereby declare that the following is a full, clear, and exact description thereof.

10 The invention relates to reversible collars.

It comprises a pair of neck bands and a folding member having upper and lower portions, the lower portion being secured between the neck bands and the upper portion being adapted to be folded over and outwardly. The folding member is of double thickness and the seams at which the two pieces of material are secured together are reduced at the front and top of the collar at the point at which the fold occurs. The object of this construction is the production of a collar of good wearing qualities, which will be readily reversible, and which, on being reversed, will conform to the neck 25 of the wearer. The smallness of the same gives the collar great flexibility at this point so that when it is reversed, it immediately assumes a proper shape, there being no suggestion of the prior deformation of the material.

Hitherto with collars of this type, difficulty has been experienced by reason of their tendency to sag, when in position on the neck, at the top and front immediately above the tie space. While on some collars the expedient of using a sewed button cooperating with a buttonhole, has been useful in preserving the shape of the collar at the front thereof, yet this construction is useless in a reversible collar, as the sewed button would be brought into contact with the neck. This construction has other disadvantages.

It is the primary object of the invention to obviate the disadvantages of this construction, and other constructions, by the provision of a collar that is snugly retained in shape at the top and front, being prevented from bulging at this point, and which is free from buttons of any kind so that no hard member is brought in contact with the neck and the greatest comfort is assured the wearer, irrespective of which side of the collar is placed interiorly.

It is an important object of the invention to provide a structure of especial stiffness immediately below the line of folding so

that there will be no wrinkling and a smooth surface is provided, thus increasing the comfort and neatness of appearance of the device.

With the above and other objects in view, which will appear as the description proceeds, the invention resides in the novel construction, combination and arrangement of parts, substantially as hereinafter described and more particularly defined by the appended claim, it being understood that such changes in the precise embodiment of the herein disclosed invention may be made as come within the scope of the claim.

In the accompanying drawing is illustrated one complete example of the physical embodiment of the present invention constructed according to the best mode so far devised for the practical application of the principles thereof, and in which:

Figure 1 is a side elevation of the collar in unfolded position.

Figure 2 is a view of the folding member in its unstitched and unfolded condition.

Figure 3 is a side elevation of one of the neck bands.

Figure 4 is a front elevation of a collar in its position as worn.

Figure 5 is a section on the line 5—5 of Figure 1, and

Figure 6 is a sectional view showing the manner in which the strap cooperates with the ends of the collar.

The fold member is of double thickness and consists of an upper portion 10 and lower portion 11. The lower portion 11 is received between a pair of neck bands 13 and 14. The neck bands are of substantially similar shape. They terminate at substantially straight front edges A and B, from which inclined edges C and D extend upwardly to corners E and F. These corners, when the collar is in the position shown in Figure 4, are at the upper extremity of the tie space. The ends of the collar are provided with holes 15 for the reception of a collar button. In the rear of the collar a hole 16 is provided, as in the common construction.

The folding member is, as above described, made of two thicknesses. These thicknesses are provided with inwardly directed seams secured by rows of stitches 17 and 18 spaced apart. The seams extend throughout the entire length of the upper portion 10 between points G and H. The seams also ex-

tend along the end edges of the folding member and are made narrow at points I and J where the member is folded. It will be observed that the folding member is spaced slightly from corners E and F.

The dimensions of the seam are such as to impart a proper degree of strength, durability, and neatness of appearance to the folding member. At points I and J the reduced dimension of the same gives the folding member especial flexibility so that after the collar has been worn, it may be folded and yet will conform at points I and J to the neck of the wearer so that the collar will not evidence in its appearance any of the prior deformations to which it has been subjected. This feature tends to enhance both the neatness of appearance of the collar at these points and also betters its wearing qualities.

20 The folding member terminates at the inwardly directed seams 19 and 20 along the lower edge of the neck bands. The folding portion and neck bands are secured together by rows of stitches 21. The seams 22 and 23 are inwardly extended along the upper edges of the neck bands and cooperate with the lower portion 11 of the folding member to impart stiffness to the collar, whereby a construction of especial smoothness free from all wrinkles results and the durability of the collar is increased.

Between the two uppermost rows of stitches 21 at each end of each of the neck bands an opening 24 is provided extending 35 through the neck band and its seam, but not through the folding member. When the collar is worn, a strap 25 is extended across the front of the tie space and hooks 26, one of

which is secured to each end of the strap, are inserted into the pair of outwardly disposed openings 24. Thus the front of the collar is secured at its upper edge from spreading and the collar is maintained erect and preserves a neat appearance.

It will be noted that the shape of the ends 45 of the band are such that two openings 24 are outwardly disposed, no portion of the neck band covering these openings. When the collar is reversed, the hooks are engaged in the remaining pair of openings and operate in substantially the same manner.

As shown in Figure 6, the hooks extend only through a neck band and its seam so that they are spaced from the neck and do not in any manner interfere with the comfort of the wearer.

I claim:—

The combination of a neck band having an opening adjacent the upper part of each of its ends, a second neck band having an opening adjacent the upper part of each of its ends, a folding member secured to said neck bands and extending downwardly between said neck bands and preventing the holes of said neck bands from communicating, a strap, and a hook secured to each end of said strap adapted to cooperate with an outwardly disposed opening for securing the upper part of the ends of said neck bands together.

In testimony that I claim the foregoing I have hereunto set my hand at Milwaukee, in the county of Milwaukee and State of Wisconsin.

FRANK TAMBORELLO.
